UNITED STATES PATENT OFFICE.

ROY KEPNER, OF ST. ELMO, ILLINOIS.

TORPEDO-SETTING DEVICE.

1,095,000.

Specification of Letters Patent. Patented Apr. 28, 1914.

Application filed July 1, 1913. Serial No. 776,861.

To all whom it may concern:

Be it known that I, ROY KEPNER, a citizen of the United States, residing at St. Elmo, in the county of Fayette and State 5 of Illinois, have invented new and useful Improvements in Torpedo-Setting Devices, of which the following is a specification.

This invention relates to devices for applying or setting signal torpedoes on railroad tracks, the primary object of the invention being to provide a device of this 10 character which is adapted to be mounted upon the rear car of a train and operated while the train is running to affix a torpedo 15 to the track, to give a signal to a following train.

A further object of the invention is to provide a torpedo setting device which may be employed for successively setting two torpedoes at a distance from each other along 20 the track when desired, and which is simple, reliable, efficient and compact in character, adapted to fold up when not in use and to be readily and conveniently manipulated.

The invention consists of the novel features of construction combination and arrangement of parts hereinafter fully described and claimed, reference being had to the accompanying drawings in which:

Figure 1 is a view elevation of the rear platform of a railway car illustrating the application of the invention thereto and showing the device as it appears after setting a single torpedo. Fig. 2 is a side elevation showing the parts of the device as

they appear just after setting a second torpedo. Fig. 3 is a side elevation showing the device in folded position. Fig. 4 is a top plan view of the parts as illustrated in Fig.

Fig. 5 is a detail view illustrating the mode of holding a torpedo in one of the clamps. Fig. 6 is a detail view of a torpedo. Fig. 7 is a view showing the torpedo applied to a track.

In carrying my invention into practice, I provide a torpedo setting device comprising a pair of setting arms 1 and 2, the arm 2 being relatively shorter than the arm 1 and pivotally connected thereto at its inner 50 end, as indicated at 3. The outer ends of the setting arms are provided with clamps 4, each consisting of a plurality of spring jaws of a character adapted to grip a torpedo 5 of the type to be set. As shown, the 55 torpedo 5 includes a spring clamp 6 having relatively diverging arms 7 adapted on

coming in contact with the head of the rail to spread upon and engage over the opposite sides of the rail head allowing the clamp 6 to firmly grip the rail and hold the torpedo 5 in position.

The setting arm 2 is adapted to fold in parallel relation to the arm 1, and to the said arms are respectively connected the outer ends of braces 8 and 9 which are pivotally coupled thereto, the brace 9 being pivotally connected at its inner end to the brace 8, as indicated at 10. By this construction the setting arms are adapted to be firmly held against deflection and guided 70 in their setting movements, and the short and long arms are respectively arranged so that said short arm may be employed alone for a setting action or the two arms operated in succession at intervals to place two 75 torpedoes at desired distances apart along a railway track.

The inner ends of the arm 1 and brace 9 are pivotally engaged with pivot pins 12 and 13 on brackets 14 and 15 fastened at 80 proper positions apart on the end of the car platform, said pins 12 and 13 facing in opposite directions and so arranged that the said ends of the arm 1 and brace 8 may be readily engaged therewith, and disengaged 85 therefrom, so that the device may be applied to and removed from a car with ease and facility. A coiled contractile spring 16 connects the arm 1 with the brace 8 and tends to draw the same together to hold said arm and 90 brace consequently in engagement with the pins 12 and 13 and to prevent casual disengagement therefrom. A chain or other lifting or controlling element 17 is attached at one end to the arm 2 and at its opposite 95 end to the end of the car. By means of this chain the short setting arm may be drawn upwardly, carrying with it the long setting arm so that the arms and their braces may be folded up and secured by means of 100 the chain or otherwise in a vertical position against the end of the car when not in use. When it is desired to employ the device for setting a single torpedo, the torpedo is fitted in the clamp 4 of the arm 2 and said arm 105 allowed to drop by gravity by letting out a portion of the chain while the arm 1 is held in an elevated position. In so dropping, the outer arm 2 will come in contact with one of the track rails and will force the torpedo into engagement therewith in an obvious manner. The arm 2 may then be

drawn up and the device secured again in folded position until its further service is desired. When two torpedoes are to be set, the arm 2 is first released and dropped to 5 apply a torpedo to the track, and at a suitable distance therefrom the arm 1 is then dropped to apply a second torpedo, the arms operating in this connection without interference so that two torpedoes may be set in 10 a reliable manner to give successive signals.

From the foregoing description taken in connection with the drawings, the construction and mode of use and advantages of my invention will be readily understood without 15 a further description, and it will be seen that the invention provides a device of the character and for the purpose set forth which will efficiently perform its intended functions and may be applied to and removed from any car equipped with pivot brackets in an easy and ready manner.

Having thus described my invention, I claim:

1. A torpedo setting device comprising a 25 pair of long and short pivoted setting arms, one of said setting arms being pivoted to the other, torpedo holding devices at the outer

ends of said arms, braces pivoted to the arms and to each other, and means connected with the shorter arm for independently raising and lowering said arm and lowering and raising the longer arm in conjunction therewith.

2. A torpedo setting device comprising a pair of spaced pivot members adapted for attachment to a car, a long setting arm pivoted to one of said pivot members, a short setting arm pivoted to said long arm, said setting arms being provided at their free ends with torpedo holding means, a brace pivoted to the long setting arm and to the other pivot member, a second brace pivoted to the first-named brace and to the shorter setting arm, a contractile spring connecting the first-named brace with the longer setting arm, and a raising and lowering element connected with the shorter setting arm.

In testimony whereof I affix my signature in presence of two witnesses.

ROY KEPNER.
